UNITED STATES PATENT OFFICE

NATHAN MICHELMAN, OF BROOKLYN, NEW YORK

WEATHERPROOF SIDEWALK DOOR

Application filed September 9, 1927. Serial No. 212,456.

This invention relates to sidewalk doors and has for its object the provision of such a door that will be entirely weather-proof, will be strong and durable, will have no 5 projections above the surface of the sidewalk and the drainage system of which will not become clogged up.

Such a structure usually consists of a frame comprising a gutter, outwardly swinging doors hinged on the frame, a gutter carried by one of the doors and so located that when the doors are closed it will collect all matter entering the crack where the doors meet and communicate with the main gutter 15 and a drainage pipe connected to the main gutter.

In such doors as made hitherto difficulty arose from the fact that a great deal of sediment would collect in the main gutter 20 around the drainage pipe thereby cutting off the rest of the gutter from said pipe and causing an overflow.

It is the particular object of this invention to overcome this difficulty and to so 25 mount the doors that when they are swung open any dirt that may have collected upon them will be deposited in the gutter rather than on the sidewalk.

Additional objects of the invention will 30 appear from the following detailed description of the drawings which illustrate the preferred form of the invention.

In the drawings similar characters of reference indicate corresponding parts in all 35 the views in which Fig. 1 is a plan view; Fig. 2 is a sectional view on the line 2—2 of Fig. 1 and Fig. 3 is a detail of the hinge shown in Fig. 2 with the door in open position.

Referring to the drawings in detail, 1 represents a steel frame having a U shaped cross-section comprising the outer wall 2 having an inwardly projecting flange 5, an inner wall 3 and bottom 4, said frame being mitred and 40 welded at the corners into an integral unit. Mounted on the outer side of the wall 3, by which is meant the side inside the frame, are a pair of brackets 6 which are narrow and substantially rectangular having an outer 45 perpendicular face 7. Journaled in said

brackets are brass rods 8 held in place by nuts or by any other common means. Fixed to said rods are the doors 9 by means of arms 10 secured to the underside of the outer edges of said doors and rigidly secured to said rods. 55 One door 9 carries at its free edge a gutter 12 which extends beyond the edge of the door and rests in a recess 13 of the frame 1 when the door is in closed position whereby it communicates with the inside of the frame. 14 60 are angle irons to reinforce the doors. The frame carries drain pipes, 11 only one of which is shown, which are secured beneath the hinge edge of the doors.

When the doors are opened the hinge edge 65 of each door swings in the arc of a circle within the gutter formed by the frame, sweeping aside any obstructions that may be formed in said gutter. Should the obstruction be in the form of a thick sludge the 70 strong agitation imparted thereto by the opening of the doors will facilitate the drawing off of said sludge by the drainage pipe. Should the obstruction be in the form of 75 walls of dirt around the pipe which dam up the liquid behind them, the opening of the doors will sweep such walls aside giving the liquid access to the drainage pipe.

As can be seen for Fig. 3, when the doors are opened the under surface of each door 80 contacts and lies contiguously with the perpendicular face 7 of the bracket 6 whereby the outward swing of said doors is limited and they are supported in upright position. It 85 will be noticed that by this arrangement any refuse that may have collected on the doors will be deposited in the gutters rather than on the sidewalk.

From the above description it can be seen that by this invention a simple, inexpensive 90 door, both as to installation and upkeep, and sanitary sidewalk is provided which lies flush with the sidewalk, has no protruding parts and is weather-proof.

Having now described the invention, what 95 is desired to be protected by Letters Patent as new and useful is:

1. In a weather-proof sidewalk door, a rectangular frame, having a U shaped cross-section with an inwardly extending flange 100

on the outer leg of said U shaped frame, brackets attached to the outer face of the inner leg of the U shaped frame, a rod journaled in said brackets at a substantial distance from the inner leg of said frame, doors mounted on said frame, brackets on the under surface near the outer edge of each of said doors and fixed to the said rod whereby when the door is opened the outer edge thereof will sweep the bottom of the said U shaped frame member.

2. In a weather-proof sidewalk door, a rectangular frame having a U shaped cross-section, brackets attached to the outer side of the inner leg of the U shaped frame and having a flat perpendicular outer edge, a rod journaled in said brackets at a substantial distance from the inner leg of said frame, doors mounted on said frame, arms mounted on the under side near the outer edge of each door and fixedly secured to said rod whereby when the door is opened its under surface will be contiguous with the outer edge of the brackets and be stopped thereby from further motion outwardly.

25. In testimony whereof I have hereunto set my hand.

NATHAN MICHELMAN.
